UNITED STATES PATENT OFFICE

ALEXANDER GRANT McGREGOR, OF LONDON, ENGLAND

ORE REDUCTION

Application filed March 28, 1929. Serial No. 350,605.

This invention comprises improvements in ore reduction and has for its object to provide a process and apparatus for the reduction of ores particularly copper ores, which is suited for continuous operation upon a large scale and wherein the reverberatory furnace required in such operations is so supplied and operated that a high efficiency is secured, temperature losses are reduced to a minimum, the handling of the ore is simplified and caking together of calcined ore before delivery to the reverberatory furnace is obviated.

In my previous United States application Serial No. 140,909, there is described an apparatus for the smelting of copper ores which comprises reverberatory furnaces arranged below groups of roasting furnaces, and connections for delivering calcined ore from the roasters to the reverberatory furnace which comprise hoppers above the reverberatory furnace to which the ore is delivered and in which it remains pending delivery to the reverberatory furnace. One of the difficulties of operation of such an apparatus lies in the fact that the calcined material tends to cake together and thereafter is difficult to feed into the furnace. The large calcine-hoppers employed moreover delivers the material into the furnace in large batches and the mass of the charge falling into the furnace by gravity tends to raise large quantities of dust. In the said prior apparatus the furnace was intended to work in the manner usual with reverberatory furnaces, large charges of ore being delivered to the furnace and melted, the product removed and a fresh charge of ore thereafter reduced. In other words, the operation was periodic or cyclic and not continuous. In operating a furnace in this fashion the furnace is liable to considerable cooling when a fresh charge of ore is introduced and the alternate heating and cooling tend to increase the fuel required.

The present invention comprises features of apparatus which are hereinafter described and which enable a furnace to be uniformly charged with ore at a plurality of points distributed along its length along each side of the furnace. Such means may comprise two main ore delivery pipes, one allocated to each

side of the furnace and means to distribute the ore therefrom.

The invention further comprises means for ensuring the continuous supply of calcine from the roasters in the case where one or more of the roasters has to be shut down, means for diverting ore to other reverberatory furnaces where one of the reverberatory furnaces has to be shut down and other features hereinafter described.

The invention further comprises a process of ore reduction in a reverberatory furnace characterized by feeding the ore to the furnace in small successive batches delivered at different points along the reaction zone of the furnace in rotation, keeping the furnace continuously in operation and periodically removing matte and slag therefrom.

The following is a description by way of example of plant constructed in accordance with this invention with reference to the accompanying drawings, in which:

Figure 1 is a section of a part of a combined roasting and reverberatory smelting plant in accordance with this invention, taken upon the line 1, 1 of Figure 2;

Figure 2 is a vertical section in a plane at right angles to the plane of Figure 1 taken upon the line 2, 2 of Figure 1;

Figure 3 is a diagrammatic plan of the plant upon a smaller scale than Figures 1 and 2;

Figure 4 is a vertical section similar to Figure 1 of a modified form of plant;

Figures 5 and 6 are details, and

Figure 7 illustrates a modified arrangement suitable for use where head room is limited.

Referring to the construction illustrated in Figures 1 to 3, the plant comprises roasters 11 of the circular hearth type arranged in groups of six above reverberatory furnaces 12, as best seen in Figure 3. Each group of six roasters is arranged in two sub-groups of three set in line with one another transversely to the length of the reverberatory furnace below. Below and between each pair of the roasters in each sub-group are calcine-hoppers 13, 14, one in each sub-group above each of the sides of the reverberatory furnace.

95

100

The outer roasters 11 are provided with chutes 15 to the calcine-hoppers and the centre roaster 11 is provided with two chutes 16 the one leading to one of the hoppers 13 and the other leading to one of the hoppers 14. These chutes are provided with suitable control means, not shown in the drawings and thus the centre roaster in each sub-group can discharge to either of the discharge hoppers 13 or 14, as desired.

Considering now the connections from the calcine hoppers to the reverberatory furnace 12, these are best illustrated in Figures 1, 5 and 6, from which it will be seen that the two hoppers 13 are connected by chutes 20 to a main ore delivery pipe 21. The pipe 21 is branched to provide a considerable number of ore inlets 22 to the furnace and the junction of each branch with the main pipe is controlled by a deflector valve the casing of which is indicated at 23. The deflector valve contains a pivoted vane 230 whereby the branch may be opened or closed from an external rock-shaft. Thus calcine flowing from either of the calcine-hoppers 13, can be directed into the furnace through any one of the branches 22. The calcine-hoppers 13 are of small size and are intended merely to take care of periodic variations and the discharge from the roasters. The ore feed to the furnace is substantially continuous, calcined ore being delivered through each of the branches 22 in rotation.

As will be seen from Figure 2, there are two sets of branches 22 and main ore delivery pipes 21, one supplied from the hoppers 13 and allocated to deliver ore to one side of the reverberatory furnace and the other being supplied from the hoppers 14 and allocated to deliver ore to the other side of the reverberatory furnace 12. At the point where the branches 22 enter the furnace they are provided with a bend or knee 24 (see Figure 6) to break the fall of the calcined ore and prevent it from entering at too great a velocity. To obviate any chance of clogging at this point the bend 24 is provided with a poke-hole 240 and a lift-up lid 241 through which a rammer may be inserted if any clogging occurs. The bend or knee 24 rests upon a water-cooled cast copper delivery chute 242 built into the angle at the junction of the roof and the wall of the furnace. Suitable links and levers may be provided, if desired, for grouping together into one place the controls of the various deflector valves 23.

Above the valves 23 and branches 22, but below the calcine hoppers 13, there is located a car-platform 25.

Rails 26 run along the platform below each of the sub-groups of the roasters and the two lines of rails are inter-connected by a cross-over 27. A junction track 28 running off to a waste dump may also be provided.

Upon the rails are cars 29 provided with cal-

cine-hoppers 30. Auxiliary discharge chutes 31 from the calcine hoppers are placed to deliver, when required, into the hoppers 30 on the cars and the hoppers themselves have discharge chutes 32 for delivering to auxiliary distributing pipes 33. The auxiliary distributing pipes deliver to the main ore delivery conduit 21 above the branches 22. Thus ore may be drawn from the roasters above any one of the reverberatory furnaces 75 and charged into the car 29 for delivery to any other of the reverberatory furnaces.

The furnace 12 is shown provided with a powdered fuel burner 40 and a hot blast supply pipe 41.

The gas exits of the roasters 11 pass upwardly, as shown at 51, and enter a dust-flue 42, which is common to all the roasters and which delivers by branches 43 to a Cottrell dust collector the finer dust, which is not shown in the drawings. The dust-flue 42 comprises dust-pockets 45 and the Cottrell or other dust collector also has dust-pockets which are indicated at 46. The dust-pockets are all connected by chutes 47, 48 to the calcine hoppers 13 and thus any dust which passes out of the roasters is collected and returned for treatment in the reverberatory furnaces.

The roasters are charged in the usual way from hoppers 48 located above them.

In the operation of this apparatus the roasters deliver continuously to the intermediate calcine hoppers 13, 14 and these deliver continuously or intermittently to the reverberatory furnaces through the main ore delivery pipe 21 and the branches 22. The branches 22 are opened one by one in rotation and only one branch is normally kept running on each side of the furnace at one time. Thus the ore may be delivered continuously to the furnace in small batches at different points in rotation and the amount charged into the furnace at any one given point can be kept down so as not to reduce the temperature of the furnace except at that point. The molten matte and slag are periodically drawn off from the furnace and this may be done without interfering with the charging operations. When all the supply branches 22 have been utilized in turn operations are recommended at the first of the branches 22 and the cycle is repeated indefinitely.

If any one, or even any two, of the roasters fall out of operation for any cause such as necessary repairs, either side of the furnace can still be kept evenly supplied by means of the other roasters in the group owing to the fact that the calcine hoppers 13 which belong to two sub-groups are connected together to supply one half of the furnace, and the calcine hoppers 14, which also belong to two sub-groups, are connected together to supply the other half of the furnace. Thus the sub-groups are interconnected and also, as the centre roasters of each group, can supply

either the hoppers 13 or 14, as desired, the discharge from the roasters of each sub-group may be mixed. Thus either one of the main ore delivery pipes 21 may be kept supplied even though any given two of the roasters should be cut out of service. The calcine from the roaster above it may be readily delivered to another furnace by means of the car-and-track system provided.

Moreover, if any one of the reverberatory furnaces has to be shut down temporarily for repairs the roasters over it may continue to operate at reduced capacity and the difficulties of getting them started up again after the reverberatory furnace is repaired can be avoided by transferring the calcine from such roasters in the calcine cars 30 to another reverberatory furnace.

The whole system is thus flexible and adaptable to meet all probable variations of operating conditions. Owing to the fact that the calcined ore is kept continuously in motion and is not long allowed to accumulate or remain at rest in the hoppers, caking is obviated, and as large charges of calcine are not fed into the reverberatory furnaces, large variations in furnace temperature are avoided.

Referring to the modification illustrated in Figure 4, it will be seen that, as before, there are roasters 11 connected to calcine-hoppers 13. Other calcine hoppers 14 for the other side of the reverberatory furnace 12 would be provided as before and likewise there is the intermediate car-platform 25 and cars 29 with associated parts. The main ore delivery pipe 21, however, instead of being provided with branches controlled by deflector valves delivers to a conveyor conduit 121 and the conveyor conduit 121 is provided with the branches 22 for delivery of the ore to the furnace. The conveyor conduit 121 is of a deep rectangular section and extends in a horizontal direction above the furnace, one conduit being located above each side of the furnace. The branches 22 are controlled by valves 123. Within the conduit 121 is a scraper conveyor 124 by which the ore is carried to the branches 22.

Referring to Figure 7 it will be seen that this is in principle similar to the arrangement of Figures 1 and 2, roasters 11 being provided above calcine hoppers 13 which are connected by a pipe system through branches 22 to a reverberatory furnace 12. Instead, however, of a single main ore-delivery pipe which receives calcine from both hoppers 13, and distributes it over the whole length of the reverberatory furnace, the chutes from the hoppers 13 unite at 121, but from this point the distribution only takes place over a portion of the length. The ends of the area along which distribution takes place are supplied by separate branches 122, 123. In other respects the arrangement is similar to Figure 1. In this case the main ore delivery

pipe may be regarded as the junction piece 121, the branches 122, 123 being subsidiary.

It is to be understood that, while this invention has been described with reference to particular embodiments thereof in the accompanying drawings, this has been done by exemplification only and the accompanying claims are intended to be read in their broadest significance. It is to be noted that although a specific arrangement of subsidiary calcine hoppers, such as 13, has been described, the disposition and arrangement of these hoppers is subject to alteration as circumstances may require.

1. claim:

1. In an ore reducing plant the combination with a reverberatory furnace and roaster furnaces disposed above the reverberatory furnace of connections for delivering calcined ore from the roasters to the reverberatory furnace which comprise two main ore delivery pipes one allocated to each side of the furnace, each of said main ore delivery pipes being adapted to pass continuously the main ore supply for the whole side of the furnace to which it is allocated, means to distribute ore to each side of the furnace from the respective main ore delivery pipes therefor and connections from a group of the roasters to each main ore delivery pipe which comprise intermediate calcine hoppers allocated one between each adjacent pair of roasters to receive calcine therefrom and to deliver said calcine to the main ore delivery pipes.

2. An ore reducing plant as claimed in claim 1 wherein the means for distributing ore from the main ore delivery pipe comprises a plurality of lateral branches therefrom to various points in the length of the furnace and said lateral branches enter the furnace by means of a bent passage, whereby the velocity of entry of the material to the furnace is checked.

3. An ore reducing plant as claimed in claim 1, wherein the means for distributing ore from the main ore delivery pipe comprises a plurality of lateral branches therefrom to various points in the length of the furnace, said lateral branches enter the furnace by means of a bent passage, whereby the velocity of entry of the material to the furnace is checked and a water-cooled delivery chute is provided from said bend into the furnace.

4. An ore reducing plant as claimed in claim 1 wherein the roasters have gas-exits which deliver to a horizontal dust flue common to a plurality of roasters, the dust flue delivers to an exit pipe, and dust-pockets are provided in said dust flue having delivery chutes to said calcine-hoppers.

5. In an ore reducing plant, the combination of a reverberatory furnace, a plurality of roaster furnaces located thereabove, hoppers below the roaster furnaces to receive the

product thereof, two main ore delivery pipes, one allocated to each side of said furnace, connections from said hoppers to said delivery pipes whereby the whole ore supply for the reverberatory furnace passes through the said two pipes, and distributing means from said main ore delivery pipes to said reverberatory furnace comprising a system of branch pipes therefrom and a valve for each of said branch pipes.

6. Ore-reducing plant as claimed in claim 5 wherein a plurality of reverberatory furnaces and roasters are employed, said hoppers being provided with auxiliary delivery means and 15 transportable receivers, and said distributing means being provided with auxiliary admission conduits; whereby product from the roasters allocated to one furnace may be transferred when desired to the distributing 20 means allocated to another furnace.

7. In an ore-reducing plant, the combination of a reverberatory furnace, roaster furnaces disposed thereabove, a plurality of calcine hoppers below said roaster furnaces to 25 receive the product thereof, and a system of inclined interconnected branching conduits beneath each of said hoppers provided with deflecting valves at said branches and adapted to direct the product from one of said 30 hoppers at will to any point desired along the length of a side of said furnace.

8. In an ore-reducing plant, the combination of a reverberatory furnace, roaster furnaces thereabove in a group which comprises 35 a plurality of roaster furnaces allocated to deliver ore to one side of said reverberatory furnace, and a plurality of roaster furnaces allocated to deliver ore to the other side of said reverberatory furnace, calcine hoppers 40 below the roasters to receive calcined ore therefrom, likewise allocated each to one side of the reverberatory furnace, one or more intermediate roaster furnaces, means to deliver calcined ore therefrom alternatively to 45 calcine hoppers allocated to either one or other side of the reverberatory furnace at will, a car-platform below the calcine hoppers but above the distributing conduits, cars on said platform, and means to divert calcined 50 ore from the calcine hoppers of one furnace to the cars, and to deliver it from the cars to the distributing conduits of another furnace.

In testimony whereof I affix my signature.
ALEXANDER GRANT McGREGOR.
